[57] CLAIM

The ornamental design for a percutaneous endoscopic gastrostomy tube, as shown and described.

DESCRIPTION

FIG. 1 is a front elevational view of a percutaneous endoscopic gastrostomy tube, showing our new design, the back elevational view being identical thereto;

FIG. 2 is a top plan view thereof;

FIG. 3 is a right side elevational view thereof, the left side elevational view being identical thereto; and

FIG. 4 is a bottom plan view thereof.
